UNITED STATES PATENT OFFICE.

GUSTAVE BERMAN, OF HOLYOKE, MASSACHUSETTS.

DESIGN FOR AN AUTOMOBILE BODY.

Application filed July 13, 1928. Serial No. 27,472. Term of patent 3½ years.

To all whom it may concern:

Be it known that I, GUSTAVE BERMAN, a citizen of the United States, residing at Holyoke, in the county of Hampden and State of Massachusetts, have invented a new, original, and ornamental Design for Automobile Body, of which the following is a specification, reference being had to the accompanying drawing, forming part thereof.

The figure is a perspective view of a body for an automobile or the like, showing my new design.

I claim:

The ornamental design for an automobile body, as shown.

GUSTAVE BERMAN.
